CONSTRUCTION SHIM

Leon F. Urbain and Matthew P. Glowacki, Chicago, Ill.;
said Glowacki assignor to said Urbain

Application November 26, 1954, Serial No. 471,386

9 Claims. (Cl. 248—354)

The present invention relates to structural elements and particularly to shims.

It is an important object of the present invention to provide a new and improved shim which is adjustable within wide limits.

Another object of the invention is to provide a sheet metal shim which is adjustable and which positively maintains its adjusted position even under great load.

Yet another object of the invention is to provide an improved shim which can be easily and readily made using conventional forming techniques.

Still another object of the invention is to provide a shim of the type set forth including means to lock the shim with respect to the overlying supporting surface positively to prevent inadvertent shifting thereof under load.

These and other objects and advantages of the invention will be better understood from the following description when taken in connection with the accompanying drawing. In the drawing wherein like reference numerals have been utilized to designate like parts throughout:

Figure 1 is a perspective view showing a shim made in accordance with the present invention in cooperation with other structural elements to support a wooden floor upon a concrete support surface;

Figure 2 is a view in vertical section substantially as seen in the direction of the arrows along the line 2—2 of Figure 1;

Figure 3 is a side elevational view showing the shim of the present invention in its lowest adjusted position in solid lines and in its highest adjusted position in dotted lines; and

Figure 4 is a plan view of the blank from which the shim of the present invention is formed.

The new and improved shim of the present application has general utility and is useful in many structural systems. In general the shim may be used wherever adjustments must be made between the level of a subjacent support and a building element which is to be laid thereon. Two specific examples of such applications are the laying of a wooden floor upon a substantially horizontal masonry floor such as a concrete floor having imperfections in the surface thereof, and in the positioning of paneling over vertical walls wherein the subjacent support is uneven and some structure must be used to insure that the exposed surface of the paneling is smooth and of the desired inclination.

There is shown in Figures 1 and 2 of the drawing, one situation in which the shim of the present invention has particular utility, namely in the laying of wooden floors upon an uneven concrete support floor. There is shown in the figure a concrete floor 10 upon which it is desired to lay tongue and groove wooden boards 12 to form a smooth and level wooden floor, for example such as a floor for a basketball court. The boards 12 are supported by a channel 14 which holds and supports clips 16 that anchor boards 12 with respect to each other

2

and with respect to the channel 14. If channel 14 and its adjacent channels are positioned level and smooth, the wooden floor made from boards 12 is also level and smooth. In those cases in which a depression or irregularity occurs in the concrete floor 10, it is necessary to provide a shim to adjust the position of channel 14 to make it level. Since the irregularities in floor 10 may be great and will vary from point to point, it is desirable to provide an adjustable shim of the present invention which is generally designated by the numeral 18. Shim 18 when properly adjusted will position channel 14 so as to make it level. An anchor member 20 passing through an aperture in channel 14 and through aligned apertures in shim 18 serves to anchor the channel 14 and shim 18 with respect to concrete floor 10, the lower end of anchor member 20 passing into and being gripped by an anchor sleeve 22 embedded in concrete floor 10.

The construction of the shim 18 will now be described in detail. Shim 18 comprises generally a substantially flat base 24 which has integrally attached thereto at one end a substantially flat side 26, base 24 and side 26 being connected by a bendable portion 28. Integrally connected to the other end of side 26 is a top or support member 30 which is connected to side 26 by a reduced bendable portion 32. More specifically, the junction between side 26 and top 30 is notched as at 34 and 36 and a pair of apertures 38 and 40 is formed in the junction also.

Attached to the other side of top 30 is a second side 42, the junction between side 42 and top 30 being a bendable portion 44 to permit ready bending between these two parts. This junction 44 is also provided with two V-shaped notches 46 and 48 and with a pair of aligned apertures 50 and 52 similar in shape and function to apertures 38 and 40 at junction 32. The other end of side 42 has a pair of notch engaging projections 54 and 56 formed thereon and extending outwardly therefrom, the angle of the surface of projections 54 and 56 with respect to the plane of side 32 being an obtuse angle. Also formed on this end of side 42 and between projections 54 and 56 is a tongue 58 which extends at an angle with respect to side 42 in a direction opposite to projections 54 and 56. The purpose of tongue 58 is to permit a workman to engage the tongue with an instrument such as a pair of pliers to aid in adjusting the height of the shim.

In order further to rigidify the various parts to take the necessary loads applied thereto in use, the base 24 is provided with a pair of side flanges 60 and 62 which extend along the length thereof and are turned upwardly at an angle of substantially 90° with respect to the plane of base 24. The side 26 is provided with a similar pair of reinforcing flanges 64 and 66, the top 30 is provided with reinforcing flanges 68 and 70 and side 42 is provided with reinforcing flanges 72 and 74. It will be seen that flanges 72 and 74 do not extend the entire length of side 42 but terminate short of the projections 54 and 56 whereby to leave these projections substantially wider than the side 42.

When the shim is in operative position the side 26 is bent at an acute angle with respect to base 24 and in order to permit such a bending the width of base 24 is substantially less than the width of side 26 so that the flanges 64 and 66 on side 26 can overlie and extend downwardly on the outside of flanges 60 and 62 formed on base 24. In operative position the top 30 is bent at an obtuse angle with respect to each of sides 26 and 42, the angle between top 30 and each of the sides being substantially equal whereby the projections 54 and 56 on side 42 extend down toward and meet base 24.

Each of flanges 60 and 62 on base 24 are cut to provide a series of teeth throughout substantially one-half

the length thereof. More particularly, the portion of flange 60 positioned away from junction 28 and side 26 is provided with a plurality of teeth 75. Each tooth 75 has a side disposed substantially perpendicular to base 24, this side being disposed toward junction 28. Flange 62 is similarly provided with a plurality of teeth 76, teeth 76 being shaped like teeth 75 and being aligned in a direction transverse to the longitudinal axis of base 24. Projections 54 and 56 on side 42 are adapted to engage with the vertical edges of teeth 75 and 76, respectively, whereby to hold shim 18 in any desired adjusted position.

In order to achieve the desired degree of adjustability, it is desirable that the base 24 be provided with as many teeth as possible so that the amount of adjustability in moving from one tooth to the next is substantially small to give substantial vertical adjustment of the shim. On the other hand the strength of the teeth 75 and 76 is increased if the number of the teeth is smaller whereby the size of each tooth is greater. It has been found that one suitable combination of the number of teeth and size of teeth is a structure in which the length of the edge of the teeth perpendicular to base 24 is approximately $\frac{1}{16}$ inch and the distance from the point of one tooth to the point of the adjacent tooth is about $\frac{5}{16}$ inch. This combination of dimensions produces a structurally strong shim with a practicable degree of adjustability.

In order to permit mounting of the shim on the floor 10, an aperture 78 is provided in top 30 in substantially the geometrical center thereof and an elongated slot 80 is formed in base 24. When shim 18 is in operative position, aperture 78 in top 30 will overlie some portion of slot 80 in any of the adjusted positions of the shim 18. When the shim is applied to a vertical support, it is necessary to prevent rotation of the shim about the fastener passing through aperture 78 and slot 80 and to this end there is provided in base 24 another aperture 82.

In forming shim 18, a blank is first cut in the shape shown in Figure 4. The same numerals have been applied to the various parts of the blank in Figure 4 so that the corresponding parts of the finished shim can be more readily recognized. It will be seen that flanges 60 and 62 are formed by bending the blank along fold lines 84 and 86, respectively, that flanges 64, 68 and 72 are formed by bending along the line 88, and that flanges 66, 70, and 74 are formed by bending along the line 90.

When using the shim 18 of the present invention in laying a wooden floor on a concrete subfloor, an anchor sleeve 22 is first inserted at the proper point in the concrete floor 10. A shim 18 is bent into the position shown in Figure 1, a channel 14 is laid thereover and an anchor 20 is passed through aperture 78 and the slot 80 into anchor sleeve 22. It is to be understood that before anchor member 20 is driven, the shim is adjusted to the approximate height. Channel 14 is then checked to determine if it is truly level and if it is found that channel 14 is not level, the shim is suitably adjusted. More specifically, if the end of channel 14 under shim 18 is too high, a workman grasps the tongue 58 with a pair of pliers and moves the projections 54-56 toward the free end of base 24 to engage the next set of teeth 75-76. Anchor member 20 is again moved to fastening position and channel member 14 checked to see if it is level. If the end of channel 14 under shim 18 is too low, then projections 54 and 56 are moved to a new set of teeth 75-76 positioned toward junction 28. When it is determined that channel 14 is level, the anchor member 20 is driven to final anchoring position. After the shim 18 has been adjusted to the final height, grouting 92 is poured around the shims 18 and the channels 14 up to the upper edge of channel 14. The grouting 92 holds the shims 18 in fixed relationship and prevents inadvertent shifting thereof.

Due to the fact that the flanges 64-66, 68-70, and

72-74 overlie flanges 60-62, the shim 18 can be moved to a very low position limited by the height of the flanges and as is illustrated in solid lines in Figure 3. A shim having the necessary structural strength has an effective height in the position shown in solid lines in Figure 3 of about $\frac{1}{4}$ inch. When adjusted to its maximum height as shown in dotted lines in Figure 3, this shim measures approximately 2 inches from the bottom of base 24 to the upper surface of top 30. This compares with shims used heretofore which have a maximum height in use of $\frac{3}{8}$ to $\frac{3}{4}$ inch.

When the shim 18 is applied to a vertical structure, no grouting is usually applied and, accordingly, additional means is necessary to prevent inadvertent shifting of the shim under load. To this end a fastener such as a screw is inserted through the opening 82 in base 24 and this fastener together with the fastener passing through aperture 78 and slot 80 will prevent inadvertent slipping of shim 18 although no grouting or other such material is used.

Although a certain preferred example of the shim of the present invention has been shown, and although certain preferred applications have been given for purposes of illustration, it is to be understood that various changes and modifications can be made therein without departing from the spirit and scope of the invention. Accordingly, the invention is to be limited only as set forth in the following claims.

What is claimed is:

1. An integral one-piece adjustable shim for adjusting the position of a load receiving member supported thereby comprising a substantially planar base, a first side having one end thereof integrally connected to one end of said base by a bendable portion, a substantially planar load bearing support member having one edge thereof integrally connected to said side by a bendable portion, a second side integrally connected to an opposite edge of said support member by a bendable portion, and means adjustably interconnecting the other end of said second side and said base whereby to position said support member at varying distances within the range of about $\frac{1}{4}$ inch to about 2 inches from said base and substantially parallel therewith.

2. An integral one-piece adjustable sheet metal shim for adjusting the position of a load receiving member supported thereby comprising a substantially planar base, a first side having one end thereof integrally connected to one end of said base by a bendable connection and disposed in use at an acute angle therewith, a substantially planar load bearing support member having one end thereof integrally connected to the other end of said first side by a bendable connection, a second side having one end thereof integrally attached to the other end of said support member by a bendable connection, and means including teeth and projections adjustably to position the other end of said second side with respect to said base whereby to position said support member at varying distances within the range of about $\frac{1}{4}$ inch to about 2 inches from said base and substantially parallel therewith.

3. An integral one-piece adjustable sheet metal shim for adjusting the position of a load receiving member supported thereby comprising a substantially planar base, a first side member having one end thereof integrally connected to one end of said base by a bendable connection and disposed in use at an acute angle therewith, a substantially planar load bearing support member having one end thereof integrally attached to the other end of said first side member by a bendable connection and disposed in use at an obtuse angle therewith, a second side member having one end thereof integrally attached to the other end of said support member by a bendable connection and disposed in use at an obtuse angle therewith, a plurality of teeth formed on the other end of said base, and a projection formed on the other end

75

of said second side member and engaging with one of said teeth to hold and position said support member at an adjustable distance within the range of about $\frac{1}{4}$ inch to about 2 inches from said base and substantially parallel therewith.

4. An integral one-piece adjustable shim for adjusting the position of a load receiving member supported thereby comprising a base, a first side member having one end thereof integrally connected to one end of said base by a bendable connection, a support member having one end thereof integrally attached to the other end of said first side member by a bendable connection, a second side member having one end thereof integrally attached to the other end of said support member by a bendable connection, a plurality of teeth formed on the other end of said base, and a projection formed on the other end of said second side member and engaging with one of said teeth to hold and position said support member at an adjustable distance within the range of about $\frac{1}{4}$ inch to about 2 inches from said base, said support member having an aperture therein and said base having an elongated slot therein, said aperture being aligned with some portion of said slot in all adjusted positions of said shim.

5. An integral one-piece adjustable shim for adjusting the position of a load receiving member supported thereby within the range of about $\frac{1}{4}$ inch to about 2 inches comprising a substantially planar base, a first side member having one end thereof integrally connected to one end of said base by a bendable connection and disposed in use at an acute angle therewith, a substantially planar load bearing support member having one end thereof integrally attached to the other end of said first side member by a bendable connection and disposed in use at an obtuse angle therewith, a second side having one end thereof integrally attached to the other end of said support member by a bendable connection and disposed in use at an obtuse angle therewith, a plurality of teeth formed on the other end of said base, a projection formed on the other end of said second side member and engaging with one of said teeth, each of said side members and said base and said support members having reinforcing flanges formed on the free edges thereof.

6. An integral one-piece adjustable shim for adjusting the position of a load receiving member supported thereby within the range of about $\frac{1}{4}$ inch to about 2 inches comprising a substantially planar base, a first side member having one end thereof integrally connected to one end of said base by a bendable connection and disposed in use at an angle therewith, a substantially planar load bearing support member having one end thereof integrally attached to the other end of said first side member by a bendable connection and disposed in use at an obtuse angle therewith, a second side member having one end thereof integrally attached to the other end of said support member by a bendable connection and disposed in use at an obtuse angle therewith, reinforcing flanges formed on the longitudinal free edges of said base, a set of teeth formed in each of said flanges adjacent the other end of said base, and a projection formed on each edge of said second side member, one of said projections cooperating with one set of teeth and the other projection cooperating with the other set of teeth to hold said support member at an adjusted position with respect to said base and substantially parallel therewith.

7. An integral one-piece adjustable shim for adjusting the position of a load receiving member supported thereby within the range of about $\frac{1}{4}$ inch to about 2 inches comprising a substantially planar base, a first side member having one end thereof integrally connected to one end of said base by a bendable connection and disposed in use at an acute angle therewith, a substantially planar load bearing support member having one end thereof

integrally attached to the other end of said first side member by a bendable connection, and disposed in use at an obtuse angle therewith, a second side member having one end thereof integrally attached to the other end of said support member by a bendable connection and disposed in use at an obtuse angle therewith, reinforcing flanges formed on the longitudinal free edges of said base, a set of teeth formed in each of said flanges adjacent the other end of said base, a projection formed on each edge of said second side member, one of said projections cooperating with one set of teeth and the other projection cooperating with the other set of teeth, and a tool engaging tongue formed on said second side member between said projections and extending outwardly therefrom.

8. An integral one-piece adjustable shim for adjusting the position of a load receiving member supported thereby within the range of about $\frac{1}{4}$ inch to about 2 inches comprising a base, a first side member having one end thereof integrally connected to one end of said base by a bendable connection, a support member having one end thereof integrally attached to the other end of said first side member by a bendable connection, a second side member having one end thereof integrally attached to the other end of said support member by a bendable connection, reinforcing flanges formed on the longitudinal free edges of said base, a set of teeth formed in each of said flanges adjacent the other end of said base, a projection formed on each edge of said second side member, one of said projections cooperating with one set of teeth and the other projection cooperating with the other set of teeth, said support member having an aperture formed therein and said base having an elongated slot formed therein, said aperture being in alignment with some portion of said slot at all adjusted positions of said shim, the end of said base opposite the connection to said first side member having an aperture formed therein.

9. An integral one-piece adjustable sheet metal shim for adjusting the position of a load receiving member supported thereby within the range of about $\frac{1}{4}$ inch to about 2 inches comprising a base, a first pair of reinforcing flanges formed on the longitudinally extending sides of said base and disposed at substantially right angles thereto, a first side member having one end thereof integrally connected to one end of said base by a bendable connection and in use disposed at an acute angle therewith, a second pair of reinforcing flanges formed on the longitudinally extending sides of said first side member, a load bearing support member having one end thereof integrally attached to the other end of said first side member by a bendable connection and disposed in use at an obtuse angle therewith, a third pair of reinforcing flanges formed on said support member, a second side member having one end thereof integrally attached to the other end of said support member by a bendable connection and disposed in use at an obtuse angle therewith, a fourth set of reinforcing flanges formed on the longitudinal edges of said second side member, a set of teeth formed in each of said first pair of reinforcing flanges on said base adjacent the free end of said base, a laterally and upwardly extending projection formed on each edge of second side member, one of said projections cooperating with one set of teeth and the other projection cooperating with the other set of teeth, and a tool engaging tongue formed on the free end of said second side member between said projections and extending upwardly therefrom, said support member having an aperture formed therein and said base having an elongated slot formed therein, said aperture being in alignment with some portion of said slot at all adjusted positions of said shim, the end of said base opposite the connection to said first side member having an aperture formed therein, the width of said base being less than the width of said support member and

said side members whereby said first pair of reinforcing flanges fit within the other pairs of reinforcing flanges.
